G. H. COTTAN.
FOLDING CHAIR.

No. 10,825.

Patented Apr. 25, 1854.

UNITED STATES PATENT OFFICE.

GEORGE H. COTTAM, OF HAMPSTEAD ROAD, ENGLAND.

PORTABLE FOLDING CHAIR-BEDSTEAD.

Specification of Letters Patent No. 10,825, dated April 25, 1854.

To all whom it may concern:

Be it known that I, GEORGE HALLEN COTTAM, of Charles street, Hampstead Road, in the county of Middlesex, England, engineer, a subject of the Queen of Great Britain, have invented or discovered certain new and useful Improvements in Chairs, Sofas, and Bedsteads; and I, the said GEORGE HALLEN COTTAM, do hereby declare that the nature of my said invention and the manner of performing the same are fully described and ascertained in and by the following statement thereof, reference being had to the drawings hereunto annexed and to the figures and letters marked thereon—that is to say, this invention consists of combining three frames, either stuffed or not, by hinges or joints, so that they fold together and form at one moment a chain or sofa, one of the frames acting as the back and at other times a bedstead, the legs or bearers being connected by movable joints to such frames, so that when required to be packed the three frames come parallel to each other and the legs or other parts also fold thereon, the arms or elbows acting by nearly a parallel movement; and in order that my said invention may be more fully understood and readily carried into effect I will proceed to describe the means pursued by me.

Description of the drawings, Plate I.—Figures 1 and 4, represent a chair constructed according to my invention and converted into a bedstead when expanded as shown at Figs. 2 and 5.

Fig. 3 is a folding squab suitable for the same. The two sides A, A, are fixed together by means of the bars k, l, m, n, or they may be connected by other suitable parts, which connect them at the back. The rod i is riveted to the front legs to keep the side frames in their position. J, O, are the two bars which form the foundation for the seat. The frames B and C, which are united together by pin joints at a and b, on which they turn, form in the chair the seat and back. E, E, are the arms which are attached by pin joints (as shown at c) to the back C, and they are united to the frame A, at a, a, by pin joints and by the curved pieces D which are connected to them by pin joints d.

Figs. 2 and 5 show the chair extended so as to form the bedstead. In this position the frames B and C (which form the back

and seat of the chair) are made to move on their joints as shown by the lines in Fig. 2, and with the frame A constitute the frame work of the bedstead, the arms of the chair reversing in this movement as shown at D and E. e e are two legs which are attached by pin joints to the frame C at h, h, and to each other by the rods f and g, (see Fig. 5,) and they support the end of the frame C. The two sides of the frame work B, B and the curved piece C are strengthened by means of the bars p, q, r, s, which act as stretchers to keep the frame apart and are riveted through the sides of B and C and on which are fixed the latching bars shown in Figs. 4 and 5 by the parts colored blue.

Fig. 3 shows the mattress or squab stuffed with hair and made in three distinct divisions, each part being adapted to the size of the three frames A, B and C.

Fig. 4 is a perspective view of the chair showing how the end of the bedstead folds up against the back rods k, l, m, n. The legs e, e, are here drawn as shut or folded close against the frame work.

Fig. 5, represents a perspective view of the bedstead as extended and ready for use; with the legs e, e, brought out to support the end. It will be evident that if this arrangement or combination were made wider it would form a sofa and bedstead.

Description of drawing, Plate II.—This drawing shows a similar arrangement or combination of chair and bedstead to that above described but differing in some of the details. Figs. 1 and 4 show the combination as a chair and Figs. 2 and 5 show the combination as a bedstead. Fig. 3 denotes the mattress. Fig. 6 shows the combination folded for transport. Figs. 7 and 8 show the joints I prefer to use but I make no claim thereto. This bedstead differs from the preceding one by reason of the legs and head board folding or shutting down nearly parallel with the sides. The legs instead of forming part of the frame in one piece as in the other chair are quite separate and are attached to the frames as shown. The iron bars F, F, connected together by the round bars k, l, m, and n form the frame of the head. The legs are prevented from falling under when in use by the peculiar formation of the joints as shown in Figs. 7 and 8 which respectively represent the joints of the two legs on each side. F is the head piece at

tached to the frame A at *a* as described. The part B of the frame work, and the part D of the arm, are connected at *p*. E is the arm of the chair, pin jointed to the frame C at *c* 5 and to D, at *d*.

Fig. 2 shows the chair extended so as to form the bedstead. In passing into this 10 position the frames B and C, which formed the back seat of the chair, are made to move at their joints as shown by the lines in Fig. 2 and now constitute the frame work of the bedstead; the arms of the chair reversing in this movement as shown at D and F. *e*, *e*, are two legs which are connected together 15 by the rods *f* and *g*. The part B on being lifted toward A releases the front leg *H*. *r*, *r*, *r*, *r* and *s*, *s*, *s*, *s* are thin plates of iron riveted to the frame work A, A and between which the parts F and B and the legs G, G 20 and H, H work into each other.

Fig. 4 represents a perspective view of the chair. The head pieces H, H are united by means of the four bars *k*, *l*, *m*, *n* against which the end frame C, C of the bedstead 25 comes to form the back. The front legs are connected together by means of the rods *v* and *w* and the hinder legs G, G are connected by the rods *t*, *u*.

Fig. 5 shows the bedstead extended in its 30 shape as a bedstead with the legs *e*, *e*, brought down to support the end, and it may be remarked that when made wide the combination becomes a sofa and bedstead as mentioned in respect to the previous one.

35 Figs. 7 and 8 are drawn half size in order to show more clearly the movements of the joints.

Description of the drawing, Plate III.—
This drawing shows the apparatus constructed as in Plate I of the drawings; but 40 in this arrangement the frames A, B, C are

stuffed on both sides in place of having a movable and separate mattress or squab. Fig. 1 shows the apparatus as a chair, the mattress being folded with the framework. 45 Fig. 2 represents the combination as extended to form a bedstead.

From the above description it will be seen that the frames A, B, C are combined in such manner that the frames A, B fold together to form the seat when the combination is in the form of a chair or sofa, and the frame C becomes the back and is supported by the head board or frame or suitable stops and it will also be seen that the 50 parts constituting the arms when the combination is in the form of chair or sofa are so arranged and combined with the frames A, B, C, that they pass below the frames when opened out into the form of a bed- 55 stead and in these particulars of combination the chairs, sofas, and bedsteads above shown and described differ from those here- 60 tofore constructed.

Having thus described the nature of my 65 invention and the manner of performing the same I would have it understood that I make no claim to the parts separately nor do I confine myself to the details as herein given provided the peculiar character of 70 my invention be retained but

What I claim is—

The mode herein described of constructing folding sofa or bedstead chairs,—viz. of a combination of three frames A, B, C and 75 jointed arms, as applied and made to operate together substantially as specified.

GEORGE HALLEN COTTAM.
